SLING TYPE CHAIR

William N. Morgan, Cambridge, Mass.

Application November 6, 1951, Serial No. 255,009

5 Claims. (Cl. 155—136)

1

This invention relates to a sling type chair. This nomenclature applies to a chair in which the flexible body sustaining member is suspended peripherally at spaced points in normally dished shape from the chair frame members, forming the seat, back and arm portions of the chair, which conform comfortably to the shape of the sitter's body under the pressure of his weight.

One of the objects of the present invention is to provide a sling type chair, the frame of which comprises upright members arranged about a vertical axis, crossing in a single joint beneath the body sustaining member, shaped below said joint to form a supporting pedestal, and above said joint having arms flaring upwardly in radial planes, from the ends of which the body sustaining member is suspended, a pair of adjacent arms being longer than the rest to define the back portion of the chair.

Another object of the invention is to provide a sling type chair as described, in which the supporting arms are inherently springy and reversely curved, whereby the advantage of the springiness can be best realized.

Still another object of the invention is the provision of a joint uniting the frame members, so constructed that the said members can be relatively displaced or partially folded about a vertical axis, so as to reduce the dimensions of the chair for purpose of storage.

A further object of the invention is to provide a joint in which the frame members are so held that they can be released, permitting the chair to be taken apart for shipment in knock-down state.

Another object of the invention is to provide a basic structural design for a sling type chair having the functional and structural attributes recited in the foregoing statements of object, equally adapted to be embodied as fine furniture for within the home, or in a more austere embodiment, as lawn or porch furniture, conveniently movable from one spot to another, and partially collapsible for storing, in seasons of disuse.

Other objects of the invention will appear as the following description of a practical embodiment thereof proceeds.

In the drawings which accompany and form a part of the following specification:

Figure 1 is a front elevation of a sling back chair embodying the principles of the invention;

Figure 2 is a side elevation;

Figure 3 is a plan view, one corner being broken away;

Figure 4 is a fragmentary view on an enlarged scale, being a plan view of the joint;

2

Figure 5 is a section taken along the line 5—5 of Figure 4;

Figure 6 is a perspective view of the joint including the adjacent portions of the frame members, exploded along a vertical axis.

Referring now in detail to the several figures, the chair consists essentially of a group of frame members 1, 2, 3 and 4 angularly displaced about a vertical axis in crossing relation to one another, being united in a single joint 5 at their point of intersection. The frame members have similar curved portions 6 below said joint, forming a pedestal support 7, said frame members above said joint being preferably reversely curved in such a manner that their upper ends 8 flare outwardly with respect to the produced axis of said joint. The body sustaining member 9 which may loosely be referred to as the seat, although it serves also as the back and sides of the chair, is of flexible sheet material which may be plastic or leather, or any other material adapted for the purpose. The member 9 is generally rectangular in peripheral contour, and has pockets 10 at the corners which are slipped over the free ends of the frame members and by means of which the member 9 is suspended from the frame members. The member 9 is inherently of dished shape and when unstressed by the weight of the sitter, the free edges between the points of suspension assume substantially catenary curvature.

An adjacent pair of the frame members, in the present illustration the members 1 and 2, are longer than the remaining frame members and serve to define the back portion of the member 9, which is higher than the front portion. The frame members are preferably of inherently springy metal in the interest of added comfort, and the frame members above the joint are reversely curved whereby full advantage of the inherent springiness of the frame can be realized. When the sitter occupies the chair, his weight causes the member 9 to conform comfortably to the shape of the body. Every change in the position or posture of the sitter results in a complementary change in the shape of the member 9, so that the sitter is always supported in the most comfortable and relaxed manner.

The characteristics of the joint by means of which the frame members 1 to 4 are united, is that it permits relative rotation of the frame members, and that it is so constructed as to enable the frame members to be completely disassembled, reducing the chair to a knock-down state. Any type of joint which cooperates with

crossed frame members to produce these results is within the purview of the invention.

By way of example, a simple and effective joint is illustrated in detail in Figure 6. The joint comprises a pair of clamp plates 11 and 12, each of which has side flanges 13 and an intermediate rib 14, defining between them parallel channels 15 and 16. Each clamp plate is designed to receive the intermediate parallel portions 17 and 18 of a pair of the frame members. The side flanges of each have the rectangular recesses 19 into which the parallel frame members fit and the intermediate rib 14 of each clamp member is sufficiently low in height to pass beneath the frame members when they are resting in the recesses 19. Each of the ribs 14 is discontinuous at the middle, to provide for the passage of a bolt 20 through a hole 21 in the clamp plate opening in the gap between the discontinuous portions of the rib. The adjacent sides of the pair of parallel frame members is provided with matching arcuate recesses 21 which fit about the bolt 20. The purpose of these recesses is to prevent longitudinal shifting of the frame members within the joint. The clamp members are provided with face plates 22 between the head of the bolt 20 and the nut 23 which screws on the opposite end of the bolt. The bolt is preferably of the carriage type, and the adjacent face plate 22 has a polygonal hole to fit the shoulder of the bolt 20 and inhibit rotation of the bolt. The clamp plates are arranged perpendicularly to one another so that the frame members are normally displaced 90° apart. Each pair of frame members consists of a long and a short member, as indicated in Figure 6.

The joint is completed by passing the bolt through aligned apertures in the clamp plates and face plates, and through the holes defined by the matching recesses 21'. When the nut 23 is tightened, the parts are held rigid.

It will be understood that the depth of the recesses 19 is the same as the thickness of the frame members, so that when the frame members are seated within said recesses they are flush with the longitudinal free edges of the flanges 13. This being the case, when the joint is together with the bolt 20 tightened the upper and lower clamping members together with the frame members which they retain, are held fixed against rotation. By loosening the bolt sufficiently to permit the clamp plates to be moved apart a distance equal to the depth of the recess 19, the frame members can clear the corner flanges 13 so that the pairs of frame members can be relatively rotated about the axis of the bolt. The extent of rotation between the pairs of frame members is limited by the engagement of adjacent frame members with one another. However, the extent of rotation of the frame members about the vertical axis of the joint is sufficient to materially reduce the dimensions of the chair so that it can be stowed in a fairly shallow closet, if need be.

By removing the bolt it is obvious that the clamp plates may be separated and the frame members completely disassociated from said clamp plates and from one another. This reduces the chair to knock-down form, making a relatively small package for shipment.

The chair specifically illustrated may be regarded as a basic structural design which is adapted to be embodied as a more or less elaborate or fine piece of furniture within the home, or may be more simply and plainly embodied as a piece of lawn or porch furniture which can be

conveniently moved from place to place, partially folded about its vertical axis for winter storage, etc., or which can be completely disassembled and reduced to minimum package form for storage or transportation.

While I have in the above disclosure described what I believe to be a practical embodiment of the invention, it will be understood by those skilled in the art that the specific details of construction and arrangement of parts, as shown, are by way of example and not to be construed as limiting the scope of the invention.

What I claim is:

1. Sling type chair comprising two similar pairs 15 of linear upright frame members arranged in crossed relation at an intermediate point, the frame members of a pair being side by side at the crossing point, the joint between said pairs comprising upper and lower channelled clamping plates receiving the frame members of the 20 respective pairs, aligned apertures through said plates and aligned recesses in the adjacent edges of the frame members of said pairs, and a bolt and nut connection between said clamping plates, 25 the bolt passing through said apertures and recesses for clamping said plates to immobilize said frame members, the portions of said frame members below said joint being relatively spread to form a supporting pedestal, the portions of said members above said crossing point also being relatively spread and one of said last named portions of each pair being longer than the other, the longer portions being relatively adjacent one another, a flexible body sustaining member suspended at peripheral points from the portions of 30 35 said frame members above said joint.

2. Sling type chair including two pairs of linear 40 resilient frame members, each member having a substantially straight middle portion and a relatively reversely curved end portions at opposite ends of said straight portions, the members of each pair having their straight portions side by side, and being arranged with their adjacent end portions curved, one upwardly and the other downwardly, the straight portions of the members 45 of one pair being superposed upon the straight portions of the members of the other pair and normally perpendicular thereto, means coacting with said straight portions for securing said pairs together, the end portions of all of 50 said members, which are below the plane of the interface between the straight portions of said respective pairs, being curved downwardly and of the same length, the end portions of all of said members, which are above said interfacial 55 plane being curved upwardly, an adjacent pair of said upwardly curved end portions being longer than the other adjacent pair, and a flexible substantially rectangular body sustaining member suspended at its corners from the tops of said 60 upwardly curved end portions.

3. Sling type chair as claimed in claim 2, said means for securing said pairs together comprising cooperating clamp plates and a bolt for tightening them, said clamp plates being constructed 65 to retain the frames of a pair side by side, and being angularly displaceable about the axis of said bolt upon loosening of said bolt.

4. In a chair, a leg unit comprising two pairs 70 of linear resilient frame members, each member having a substantially straight middle portion and relatively reversely curved end portions at opposite ends of said straight portions, the members of each pair having their straight portions side by side and being arranged with their adjacent end portions curved, one upwardly and

the other downwardly, the straight portions of the members of one pair being superposed upon the straight portions of the members of the other pair and normally perpendicular thereto, means coacting with said straight portions for securing said pairs together, the end portions of all of said members, which are below the plane of the interface between the straight portions of said respective pairs being curved downwardly and being of the same length, the end portions of all of said members which are above said interfacial plane being curved upwardly.

5. Leg unit as claimed in claim 4, said means for securing said pairs together comprising co-operating clamping plates and a bolt for tightening them, said clamp plates being constructed for

retaining the frames of a pair side by side, and being angularly displaceable about the axis of said bolt upon loosening of said bolt.
